COMBINED METAL-WORKING MACHINE

1,117,101.

Specification of Letters Patent.

Patented Nov. 10, 1914.

Application filed July 18, 1906, Serial No. 326,683. Renewed April 27, 1914. Serial No. 834,818.

To all whom it may concern:

Be it known that we, MAX SKLOVSKY and GEORGE W. MIXTER, citizens of the United States, residing at Moline, in the county of Rock Island and State of Illinois, have invented certain new and useful Improvements in Combined Metal-Working Machines, of which the following is a specification, reference being had therein to the accompanying drawing.

Our invention has for its object to produce a machine that is adapted to apply a nut to a bolt and then to upset or rivet the head of the bolt and to perform these operations rapidly and in the proper sequence.

In the accompanying drawings, Figure 1 is a vertical sectional view of a machine embodying our improvements. Fig. 2 is a front view of the same. Fig. 3 is a central vertical section of the riveting portion of the machine drawn on a larger scale than the views thus far described. Fig. 4 is a top plan view of the valve device of the hammer or riveting mechanism. Fig. 5 is a central vertical section taken on the line 5, 5, of Fig. 4. Fig. 6 is a bottom plan view of the cylinder in which the hammer or riveting tool reciprocates. Fig. 7 is a detached view of the shaft that operates the valve of the hammer or riveting mechanism. Fig. 8 is a transverse section on the line 8, 8, of Fig. 3. Fig. 9 is a central sectional view of the main controlling valve. Fig. 10 is a bottom plan view of the valve. Figs. 11 and 12 are, respectively, a side and a bottom plan view of the movable controlling disk of this valve.

The several parts of the apparatus which is represented are adapted to be operated by compressed air, though other motor fluid may be employed if that be found desirable. We have represented the apparatus as being used to apply a nut *a* to a bolt *b*, these in turn serving to unite two parts, such as a metal plate *C*, which might be a plow-share, or a wooden beam or piece *D*. The mechanism is mounted in a single substantial frame, designated as a whole by 2, and provided with a lower shelf, platform or bracket portion 3, upon which is supported and secured the riveting mechanism or pneumatic hammer, and an upper shelf, platform or bracket portion 4 upon which are supported the mechanisms for applying and setting the

nut. These latter mechanisms are preferably arranged within a housing 5 provided with a separable cover 6.

Within the housing there is arranged and suitably supported a pneumatic engine 7, 60 adapted to rotate the shaft 8. As this engine may be of any usual or preferred construction, it is not illustrated at all in detail. The motor fluid for operating the engine may be supplied through the connection 9.

10 is a gear wheel secured to the shaft 8 and meshing with another wheel 11 that is splined to a shaft 12 mounted in the forward portion of the housing, which may be 65 especially shaped to receive it, as indicated at 13. The shaft extends through the bottom wall 14 of the housing and carries at its lower end a wrench 15 shaped to fit the nut *a*. The shaft 12 is longitudinally adjustable in order that the wrench tool may be moved toward and from the nut and that it may follow the nut as the latter is screwed upon a bolt by the rotation of the shaft. The shaft normally is elevated, that is, is 70 moved away from the support 16 upon which the work rests during the nut setting and riveting operations, this position of parts being represented in Fig. 2, while in Fig. 1 the parts are shown in their working positions. A spring 17 operates to maintain the wrench and its operating shaft in an elevated position. This spring is preferably of the coiled variety and encircles the shaft 12, one end resting against the 75 bottom plate 14 of the housing as a stationary abutment, and the other end against a set collar 18 and movable with the shaft 12. The wrench is moved into engagement with the nut and there held by pneumatically operated apparatus, which is arranged to come into operation just before the motor 7 starts, so that the wrench is first engaged with the nut and is then turned to screw the nut upon the bolt, this sequence of operations being 80 insured by suitable valve mechanism controlling the flow of the motor fluid to the respective engines or motors.

19 represents a small cylinder supported upon the top plate 6 of the housing in line 85 with the shaft 12. Within the cylinder is mounted a piston 20, and a supply pipe 21 conducts the motor fluid that acts upon the piston to the cylinder. The piston has engagement with the shaft 12, and when acted 90

upon by the motor fluid forces the shaft downward, against the action of the spring 17, so as to bring the wrench into engagement with a nut which may have been placed 5 in position, the parts which the nut and its bolt are to unite resting upon the supports 16. From that face of the piston which is toward the shaft extends a pin 22 that enters a recess formed therefor in the end of 10 the shaft, the engagement thus produced between the piston and the shaft being sufficiently loose to permit the free rotation of the shaft without correspondingly turning the piston.

15 It will be seen from the foregoing description, taken in connection with the drawings, that we have produced a nut-setting apparatus comprising two independently-acting motors, one operating to hold the wrench in 20 engagement with the nut, and the other to rotate the wrench and through it the nut. When the resistance of the nut becomes greater than the power of the motor 7, the latter and the parts driven thereby merely 25 cease to move, pressure upon the parts however being maintained so long as the motor fluid is delivered to the respective motors. It is often desirable to upset or rivet the head of a bolt after a nut has been applied 30 thereto and screwed tightly in place, and we will now describe the mechanism by which this operation is effected.

The pneumatic hammer or riveting tool is secured in place by suitable clamping or 35 holding means 23 upon the lower platform or bracket part 3 of the main supporting frame. The frame or casing of the riveting tool or mechanism consists essentially of two parts secured together by bolts 24, or otherwise, the upper part 25 being constructed 40 to receive and support the reciprocating hammer or upsetting tool 26, and the lower part 27 to receive and support the movable element of the valve mechanism.

45 The upper member 25 of the casing of the pneumatic riveting tool is formed with a central axially-disposed chamber 28, in which is secured a cylinder 30 that constitutes the working cylinder of the riveting 50 tool or engine. The hammer or tool 26 is mounted in a sleeve or bushing 31 secured in the upper portion of the member 25 and by which it is guided and directed in its movements. It is provided at its inner end 55 with a head or piston 32 that fits the cylinder 30 and moves therein, its opposite ends or faces being alternately acted upon by the motor fluid to cause its rapid reciprocations in the manner presently to be described. 60 The stem of the reciprocating tool or hammer is of relatively large diameter and is preferably hollow, as indicated at 48, in order that the effective areas of the opposite faces of the piston, against which the motor fluid alternately acts, may be widely differ-

ent—that on the upper side of the piston being the relatively small annular face surrounding the large stem, while the opposite surface, against which the motor fluid acts to force the tool outward to strike the blow, 70 is of an area practically equal to the cross-area of the piston head.

The cylinder 30 is preferably provided at its lower or inner end with a head 33 occupying a recess or chamber 34 in the upper 75 end of the casing member 27. This head is formed with an outward-extending flange 35, perforated at suitable intervals to permit the passage of the screws or bolts 36 which serve to securely unite the cylinder and its 80 head with the upper member of the pneumatic hammer casing. Through the head 33 there are formed two sets of apertures 37, 38, which are preferably arranged concentric with the axis of the cylinder 30. The 85 apertures 37 of one set communicate with chambers or ducts 39 for the motor fluid formed in the body of the upper casing member 25, while the apertures or ducts 38 of the other set communicate with the interior 90 of the cylinder 30.

The motor fluid for operating the pneumatic hammer is conducted thereto through a pipe 40, and passage 29, the latter communicating with one of the motor fluid 95 chambers 39. The chambers 39 communicate with each other at their upper and lower ends—they being separated merely for structural purposes—so that the motor fluid can freely act upon the head or piston of the 100 riveting tool 26. In the upper face of the head 33 there is formed an annular groove or channel 41 that serves as a communication between the several ducts or apertures 37 as well as between the lower ends of the several 105 chambers 39.

In the lower casing member 27 there is formed a second chamber 42 directly below the chamber 34, communicating therewith, and preferably of smaller diameter. In this 110 latter chamber there is situated the valve 43 that controls the admission and exhaust of the motor fluid to and from the working cylinder 30. This valve is of cylindrical disk shape, fits within the recess or chamber 42 115 closely, and is held against the lower face of the head 33 containing the motor fluid ducts 37 and 38. Extending through the valve are the apertures 44, which preferably at their lower ends enter an annular groove 120 or channel 45 formed in the face of the valve and serving as the means of communication between the several apertures or ducts. There are as many of these apertures or ducts as there are ducts or apertures 38 in 125 the head 33, and they are so disposed that when the valve is in suitable position the ducts of one set register with those of the other. There is also formed a channel or groove 46 in the upper face of the valve, 130

from which lead short radially-disposed ducts or channels 47 extending toward the center of the valve, each arranged midway between a pair of apertures 44, as clearly represented in Fig. 4.

The manner of operating the pneumatic hammer can now be stated. If the valve be adjusted to the position indicated in Fig. 3, that is with the radially-disposed ducts 47 opposite the lower open ends of the apertures 38, the motor fluid entering the chambers 39 passes therefrom through the ducts or apertures 37 into the channel 46 in the upper face of the valve and from there it passes through the ducts 47 to the apertures 38 by which it is led into the cylinder 30 below the piston or head of the hammer or riveting tool. This causes the latter to be forced upward into the position indicated in Figs. 1 and 3, that is into position to strike a blow. At the same time the motor fluid is acting upon the upper exposed face of the piston, but as the area of this is so much less than that of the opposite or lower face the effect is but slight and may be neglected. After the tool has been advanced to strike a blow the valve is adjusted to bring the upper ends of the apertures or ducts 44 therein opposite to the lower open ends of the ducts 38, and as the ducts 44 communicate with the exhaust the result is that the interior of the cylinder 30 is connected with the exhaust and at the same time cut off from the motor fluid supply. The hammer is retracted, its head 32 moving downward into the cylinder 30 by reason of the action of the motor fluid upon the annular upper face of the piston. It will be observed that the apertures or ducts 38 open into the cylinder 30 at some distance above its lower end, so that when the hammer is moved inward its piston closes the inner ports of the air ducts before the end of the piston head reaches the lower end of the cylinder, thereby forming an air cushion that prevents disastrous shocks to the apparatus. The piston is not packed and hence does not fit the cylinder air-tight, so that when the motor fluid pressure is admitted to the ducts 38 there is sufficient leakage past the piston to start its upward movement, slowly at first, but after the inner ports of the ducts 38 are uncovered, admitting the full force of the motor fluid to the inner end of the piston, with increasing speed and force.

In order to effect the movements of the valve 43 we prefer to employ the following instrumentalities: 49 is a shaft mounted in the lower casing member 27 and provided at its upper end with a cross-head 50 that is adapted to engage with the valve, the latter being provided with a recess 51 in its lower face to receive such cross-head. The cross-head is held in close engagement with the

valve, and the latter in turn tightly against the under face of the head 33, by a coiled spring 52 situated in a recess 53 provided therefor in the casing member 27. A pulley 54 is mounted upon the shaft 49 and is connected by a belt 55 with another pulley 56 on a suitable driving shaft 57. Through this train of gearing the valve is rotated. A duct or passage 58 extends axially through the shaft 49 and constitutes the exhaust passage for the motor fluid. The course of the exhaust from the cylinder 30 is through the ducts 38 and 44 into the channel 45 which opens into the recess 42 in which extends the end of the shaft 49. From this chamber the spent motor fluid passes freely into the open through the duct 58. The valve 43 is provided at its upper side with a screw-threaded socket 59 into which is screwed a post 60 that extends upward axially through the cylinder 30. The post is provided with one or more longitudinal grooves 61 into which extends pins 62 rigidly secured to the hammer or reciprocating tool 26. As the post 60 is secured fast to the valve, and is connected, as described, with the hammer, it follows that while the latter is free to reciprocate it is caused to rotate with the valve, with the result that the striking end of the head of the hammer is presented to the rivet or work being acted upon at different angular relations at the moments of delivering successive blows.

The motor fluid for operating the several engines or motors which have been described may be received from a single source, and we prefer that the several supply pipes, 9, 21 and 40 should be connected with a three-way valve device 63 arranged to be operated by an attendant in any suitable manner. This valve, which is illustrated in Figs. 9 to 12, is so constructed as to admit the motor fluid to the several engines in proper sequence,—first to the cylinder 19, in order to set the wrench upon the nut, next to the engine 7 to cause the nut to be screwed upon the bolt, and finally to the pneumatic hammer to cause the upsetting or riveting of the head of the bolt. As indicated in the drawings, this valve consists of a valve casing 64 provided with a removable head 65. Within the chamber of the casing there is arranged a close-fitting disk or head 66, mounted upon a stem 67, to which is secured the operating handle 68. The disk 66 is held close against the head 65 of the casing by a spring 69. The chamber above the head communicates with the open air through apertures 70. The head of the valve casing is perforated to receive the several fluid pipes, of which the one, 71, is the supply pipe for the motor fluid, and is preferably centrally located, while the others, 9, 21 and 40 lead, respectively, to the several engines, as already described.

In the face of the disk next to the head 65 is formed a branching channel illustrated in Fig. 12. The channel has a central portion 72 that stands opposite to and is in constant communication with the supply or inlet pipe 71. The branch 73 of this channel terminates in an elongated concentrically-disposed portion 73', that is adapted to register with the port 21' in the head of the valve 10 casing that leads to the pipe 21 that supplies the motor fluid to the wrench-setting engine. Branch 74 likewise terminates in a concentrically-disposed portion 74', that is adapted to register with the port 9' that 15 communicates with the pipe 9 that supplies the rotating engine 7 that sets the nut. The portion 74' of this branch is not so long as the portion 73' of the other branch, because, as has been described, the motor fluid is on 20 the engine 19 for a greater length of time than it is upon the engine 7. The branch 75 communicates with the port 40', and when the disk has been turned to the proper position this puts the riveting engine in connection with the supply. There are likewise 25 formed in the head or disk 66 a series of exhaust passages 76-77-78, adapted to communicate, respectively, with the ports 21', 9', and 40'. Preferably the exhaust passages 30 77 and 78 are elongated, as indicated in Fig. 12.

It will be apparent from the foregoing description, taken in connection with the drawings, that the rotation of the valve disk 35 66 in the direction of the arrow, Fig. 12, will first put the wrench-setting cylinder 19 into communication with the motor fluid supply, and that such communication will be maintained throughout the entire operation of the apparatus, this being insured by the elongated portion 73' of the supply channel. Next, the engine 7 is connected with the motor fluid supply, and finally the riveting tool or hammer is connected up 40 therewith. The hammer continues to operate so long as the attendant holds the disk 66 in the farthestmost position of movement, in the direction indicated by the arrow, (Fig. 12), the other engines being mean- 45 while supplied with motive fluid and hence operating, the one to press the wrench downward so that it constitutes an abutment against which the riveting tool may work, and the other to maintain a turning 50 stress upon the wrench. When the rivet has been set the attendant reverses the motion of the disk. This first cuts off the supply of motor fluid from the riveting engine, and then immediately connects its cylinder with 55 the exhaust through the passages 78 and 70. Next, the motor fluid is cut off from the rotating nut-setting engine 7, and its cylinder is opened to the exhaust through the passages, including those designated 77 and 70; 60 and finally the motor fluid is cut off from

the cylinder 19, which is put into communication with the exhaust through passages which include those indicated at 76 and 70. By reason of the passages 78 and 77 being elongated, the riveting and nut-setting engines remain connected with the exhaust until, and so long as, the engine 19 is connected therewith. 70

It will be understood that power is applied to the several motors so long as the valve is kept open, so that if the riveting operation should result in any loosening of the bolt in its seat, as is frequently the case, such looseness will be taken up by the tightening of the nut to which pressure is constantly applied through the wrench and the two motors that act thereupon. 75

As the shaft 57 may be constantly or intermittently driven as desired, we have not deemed it necessary to show the connections 80 of the driving mechanism therefor. 85

In practice, the shaft 49 is caused to make about sixty revolutions per minute and, as there are twelve apertures 44 in the valve and a like number of apertures 38 in the head 33, it follows that there will be approximately seven hundred reciprocations of the hammer per minute when the parts are run at the speed stated. 90

We do not herein claim the particular 95 riveting mechanism which we have shown and described as this is covered by our co-pending application for riveting machines, Serial No. 690,991, filed April 15, 1912, as a division of this application. 100

What I claim is:—

1. In a machine for effecting bolt fastenings, the combination of a wrench adapted to engage the nut, means for turning the wrench to screw the nut upon the bolt, and 105 means for riveting or upsetting one end of the bolt arranged to operate upon the bolt while it is in position to be engaged by the wrench, substantially as set forth.

2. In a machine for effecting bolt fastenings, the combination of a wrench adapted to engage the nut, means for turning the wrench to screw the nut upon the bolt, and means for riveting or upsetting the head of the bolt arranged to operate upon the bolt 115 while it is in position to be engaged by the wrench, substantially as set forth.

3. In a machine for effecting bolt fastenings, the combination of means for turning the nut to screw it upon the bolt, means for 120 riveting or upsetting one end of the bolt arranged to operate upon the bolt while the latter is in position to be engaged by the nut-turning means, and means to support the work against movement while it is being 125 operated upon, substantially as set forth.

4. In a machine for effecting bolt fastenings, the combination of means for screwing the nut upon the bolt, means for riveting or upsetting one end of the bolt, and means 130

for causing the simultaneous operation of the nut-screwing means and the riveting means, substantially as set forth.

5. In a machine for effecting bolt fastenings, the combination of means for screwing the nut upon one end of the bolt, means for riveting or upsetting the opposite end of the bolt, and means for causing the simultaneous operation of the nut-screwing means 10 and the riveting means, substantially as set forth.

6. In a machine for effecting bolt fastenings, the combination with a support for the work, of means for setting the nut upon the bolt arranged to one side of the said support, means for upsetting or riveting one end of the bolt to which the nut has been applied arranged on the opposite side of the holder or support, and means for operating 20 the said parts, substantially as set forth.

7. In a machine for effecting bolt fastenings, the combination of the wrench, a shaft carrying said wrench, means for turning the shaft, means for moving the shaft endwise 25 to bring the wrench into engagement with the nut, and maintaining pressure thereon in the direction of said movement, and riveting means arranged in line with the shaft to upset the head of the bolt, substantially 30 as and for the purpose set forth.

8. In a machine for effecting bolt fastenings, the combination of a wrench, a motor for moving the wrench into engagement with the nut, a motor for turning the 35 wrench to screw the nut upon the bolt, a hammer, or tool for riveting or upsetting one end of the bolt, a motor for operating the said riveting or upsetting tool, and a valve device controlling the admission of 40 motive fluid to the said motors, constructed to bring them into operation in the order named, substantially as set forth.

9. In a machine for effecting bolt fasten-

ings, the combination of a wrench, a motor for moving the wrench into engagement 45 with the nut, a motor for turning the wrench to screw the nut upon the bolt, a hammer or tool for riveting or upsetting one end of the bolt, a motor for operating the said riveting or upsetting tool, and a 50 controlling device for bringing the said motors into operation in the order named, substantially as set forth.

10. In a machine for effecting bolt fastenings, the combination of a wrench, a motor 55 for moving the wrench into engagement with the nut, a motor for turning the wrench to screw the nut upon the bolt, a hammer or tool for riveting or upsetting one end of the bolt, a motor for operating 60 the said riveting or upsetting tool, and a valve device controlling the admission of motive fluid to the said motors constructed to bring them into operation in the order named and to maintain the first two under 65 pressure while the riveting operations take place, substantially as set forth.

11. In a machine for effecting bolt fastenings, the combination of a wrench, a motor for moving the wrench into engagement 70 with the nut, a motor for turning the wrench to screw the nut upon the bolt, a hammer or tool for riveting or upsetting one end of the bolt, a motor for operating the riveting or upsetting tool, and a device for 75 controlling the operation of the said motors adapted to bring the riveting motor into operation after the wrench motors, substantially as set forth.

In testimony whereof we affix our signatures, in presence of two witnesses.

MAX SKLOVSKY.
GEORGE W. MIXTER.

Correction in Letters Patent No. 1,117,101.

It is hereby certified that in Letters Patent No. 1,117,101, granted November 10, 1914, upon the application of Max Sklovsky and George W. Mixter, of Moline, Illinois, for an improvement in "Combined Metal-Working Machines," an error appears in the printed specification requiring correction as follows: Page 1, line 47, for the word "or" read ~~to~~; and that the said Letters Patent should be read with this correction therein that the same may conform to the record of the case in the Patent Office.

Signed and sealed this 15th day of December, A. D., 1914.

[SEAL.]

J. T. NEWTON,
Acting Commissioner of Patents.
